PORTABLE PROJECTION SCREEN

John Leslie Stableford, London, England

Application April 12, 1945, Serial No. 587,922
In Great Britain April 21, 1944

13 Claims. (CL. 160—24)

This invention concerns improvements in portable projection screens particularly intended for use in exhibiting cinematograph films, lantern slides and so on in halls, in the rooms of houses and other buildings, in ships and in like places having other main uses and only temporarily employed for these exhibitions, and the invention is more particularly concerned with collapsible projection screens of the kind where the screen, when not in use, is housed in a box which forms a base for the extended screen. One such form of collapsible portable screen is described in the specification of my co-pending application No. 512,103, filed Nov. 29, 1943. This screen comprises a box in which the screen is housed when collapsed, the screen being rolled upon a spring roller to which it is attached at one end, this spring roller being mounted upon a supporting structure which, together with a rigid member attached to the free end of the screen, constitutes the said box. The said rigid member serves as a lath at the free end (i. e. the end remote from that attached to spring roller) of the screen and is connected to the said roller supporting structure by a pair of similar foldable or articulated struts each formed by a pair of links hingedly connected together at one end, one end of each articulated strut being pivotally connected to the said lath and the opposite end of each strut being pivotally connected to the roller supporting structure.

In portable screens of this character it is highly desirable to make a box of the smallest possible dimensions to reduce its bulk and weight. The length of the box is more or less fixed by the width of the screen but it is possible to construct a screen, in accordance with my patent application No. 512,103 for example, in which the front to back width of the box is quite small and not very much in excess of the overall diameter of the rolled up screen. However, when the box is made narrow in this way it is unstable when the screen is erected unless some form of stabilising means are provided, as for example the stabilising bars described in the specification of my said patent application No. 512,103. These stabilising bars are detachable and there is consequently a possibility that they may be lost; it is an object of this invention to eliminate this possibility whilst a further object of the invention is to provide an improved stabilising means whereby, inter alia, the effort and time required to erect the screen for use may be further reduced. This invention therefore concerns, inter alia, improvements in or modifications of the invention claimed in the

specification of my said application No. 512,103.

According to the invention there is provided a portable projection screen of the kind comprising a long box in which the screen sheet is housed when collapsed and from which it extends upwardly when in use, wherein the box is furnished between its ends with one or more pairs of openings, one opening of each pair being provided in the front wall of the box and the other in the rear wall of the box, and wherein one or more stabilising members is or are provided which is or are movable relatively to the box so as to be capable of being disposed in a screen stabilising position in which it projects or they project from within the box forwardly and rearwardly through the said openings and beyond the box.

According to a further aspect of this invention the box adapted to house the collapsed screen and to form a base for the erected screen, is provided with at least one stabilising member, this member being attached to the box and disposed upon or adjacent the upper side of the bottom of the box in such a way as to be movable with respect to the said bottom either into an out-of-the-way or stowed position in which it is wholly or mainly housed within the box, or into an operative position in which a portion or portions of the stabilising member projects or project transversely from the box through slot or opening means in the longitudinal wall or walls of the box so as to increase the effective width of the bottom of the latter.

The said stabilising member may comprise a rigid flat or mainly flat element (formed, for example, of wood or metal) centrally pivoted (e. g., by a bolt or rivet) to the upper side of the bottom of the box, such element being greater in length than in width, and the width of the element being preferably equal to, or approximating to, the width of the bottom of the box so that when turned into its out-of-the-way position the element is wholly disposed within the external surface of the box, but when the element is turned into its operative position portions of the element extend through the slots or openings in the front and rear walls of the box and forwardly and rearwardly respectively beyond these walls.

Preferably stop means are provided to limit the extent to which the stabilising member may be moved. Thus, when the stabilising member is in the form of a centrally pivoted element as above described, an end of one or each of the slots in the front and rear walls of the box may co-operate with an edge of the stabilising element

to limit the angle through which it may move, preferably to approximately 90°.

The slots in the front and rear walls of the box through which the projecting ends of the stabilising member extend when the member is in use are preferably such that the said walls bear upon the upper surface of the stabilising member so as to relieve the pivot of the member of, or of most of, the strain borne by the stabilising member when the screen is in use.

The ends of the stabilising member are provided with feet portions adapted to engage the surface upon which the screen box is stood. These feet would ordinarily be of a height equal to the thickness of the base of the box, and they may be integral with or attached to the stabilising member or partially integral and partially attached. They may thus be formed wholly or partially as pads of a relatively soft material such as, for example, rubber or felt. Recesses 20 may be provided in the front and rear edges of the bottom of the box to receive these feet when the stabilising member is in its out-of-the-way position.

Preferably the stabilising member has two straight parallel sides which, when the member is in the out-of-the-way position, are coincident respectively with the front and rear edges of the bottom of the box. The end portions of the stabilising member may be rounded, or of triangular or any other suitable shape. Thus, for example, the stabilising member may be, in plan, in the form of a strip equal in width to the bottom of the box and provided with rounded ends, or in the form of a parallelogram the width between the parallel sides of which is equal to the width of the bottom of the box, or it may be of approximately diamond shape.

In order that the invention may be more readily understood certain embodiments of the same will now be described, by way of example only, as applied to a portable projection screen of the form described in the specification of my patent application No. 512,103, such embodiments being shown in the accompanying drawing, in which:

Figure 1 is a broken perspective view of a portable projection screen in the open condition;

Figure 2 is a part section on line II—II Figure 1 and is drawn to a larger scale than Figure 1;

Figure 3 is a view similar to Figure 2 but shows the stabilising member in its inoperative position;

Figure 4 is a section on line IV—IV Figure 1, this figure also being drawn to a larger scale than Figure 1;

Figure 5 is a view similar to Figure 2 and shows a modified form of stabilising means; and

Figure 6 is a further view similar to Figure 2 and shows a still further modified form of stabilising means.

Referring to Figures 1 to 4 it will be seen that the portable projection screen there illustrated comprises a long rectangular wooden box generally indicated by the reference 1. Within the box is housed a spring roller 2 to which one end of a flexible rectangular sheet 3 adapted to be wound on to the roller and having the end thereof, opposite to that attached to the roller 2, fixed to the underside of a lath 4 also serving as the lid of the box 1.

The lath or lid 4 is connected to the back wall 5 of the box 1 by a pair of articulated struts 6 and 7, the lower links 8 and 9 of which are pivoted, at a distance from their lower ends, to the upper part of the said rear wall 5. The lower extremity of each of said lower links 8 and 9 is

connected by a spring, such as that marked 10 in Figure 4, to a bracket 11 on the rear wall 5 of the box. A screen such as so far described is in accordance with my hereinbefore mentioned patent application No. 512,103.

In applying this invention to the screen at least one stabilising member 12 is provided. This member is formed from a piece of wooden strip of the same width as the bottom 13 of the box and having its end portions cut obliquely so that the stabilising member is of parallelogram shape in plan. The stabilising member so formed is laid flat upon the upper side of the bottom 13 of the box and a bolt or rivet 14 is passed through the 10 stabilising member at the intersection of its diagonals and through the bottom of the box on the longitudinal centre-line thereof to constitute a vertical pivot about which the stabilising member may turn in a plane parallel to the upper surface of the bottom of the box. If two or more stabilising members are employed instead of only one, then the stabilisers are longitudinally spaced along the bottom of the box.

For the, or each, stabilising member 12 the front wall 15 and the rear wall 5 of the box are provided respectively with longitudinal openings or slots 16 and 17 adjacent the bottom 13 of the box, these slots extending transversely through the said walls and being of approximately the same length as, and relatively longitudinally offset to the same degree as, the longitudinal parallel sides 18 and 19 of the stabilising member.

At least one end of each of the slots 16 and 17 is cut obliquely at 20 so as to lie along and engage 35 as stop means the oblique end edges 21 and 22 of the stabilising member when this is in the inoperative position shown in Figure 3. The ends 20 of the slots 16 and 17 also engage the edges 18 and 19 of the stabilising member 12 when in its operative position (as shown in Figure 2) to limit the opening movement of the member. The said slots are approximately equal in depth to the thickness of the stabilising member.

At each of its diagonally opposite acute angled corners, and on its underside, the stabilising member is provided with a foot 23 equal in height to the thickness of the bottom 13 of the box, which bottom is provided at its front and rear edges with recesses 24 to house the said feet when the 45 stabilising member is in its out-of-the-way position. These recesses are preferably sufficiently large, or have their edges chamfered off on the underside at 25, to enable a finger to be inserted behind the foot of the stabilising member to facilitate the pulling out of the said member from the inoperative to the operative position.

When the stabilising member is extended to its operative position as shown in Figures 1, 2 and 4, the feet 23 rest upon the surface upon 60 which the box 1 is placed and so form a forward and rearward extension of the base of the box and serve to stabilise it against tilting over backwardly or forwardly. Furthermore any strain to which the stabilising member may be subjected 65 in performing its work is taken by the front and rear walls of the box and not the bolt 14 since the said walls bear upon the upper side of the stabilising member. When not in use the stabilising member is housed entirely within the compass of the box 1 as clearly shown in Figure 3.

If desired, instead of making the stabilising member in one piece as above described, it may, as shown in Figure 5, be made in two parts 26 and 70 27 halved together at their inner ends and hinged on a common pivot 28 within the box and each

adapted to be swung out of the box through the corresponding slot 29 or 30 in the longitudinal rear or front wall of the box into the projecting operative position. If desired the two parts 26 and 27 may be carried by separate pivots.

Alternatively, as shown in Figure 6, a stabilising member made in two parts 31 and 32 may have these parts arranged to slide endwise into and out of the box transversely to the length of the latter, the lengths of the parts of the stabilising member being transverse to the length of the box, and the said parts being guided in openings 33 and 34 in the front and rear walls of the box and also in brackets 35. To limit its outward movement each part 33 and 34 may have a stop plate or part 37 at its inner end to engage the bracket 35.

It will be understood that according to the above described embodiments of the invention the stabilising means are unitary with the box, that when not in use they are completely disposed within the outer dimensions of the box; when in use they are firmly supported between the bottom and the front and rear walls of the box; the stabilising means may be quickly and easily moved into or out of operation; and that when the stabilising means are in the inoperative position the openings through which they pass when in use, are closed.

What I claim is:

1. A portable projection screen comprising a box, a screen sheet adapted to be extended upwardly from said box for use and to be housed in the box when not in use, said box having at least one pair of openings between its ends, one such opening of each pair being provided in the front wall and the other in the rear wall of the box, and a stabilising member for each pair of said openings, said stabilising member being movable relatively to the box for disposal alternatively in a stowed position and in an operative position wherein it projects from within the box forwardly and rearwardly through the said openings in the front and rear walls of the box, and beyond the box.

2. A portable projection screen comprising a long box, opening means in the perimeter of said box, a screen sheet adapted to be extended upwardly from the box for use and to be housed in the box when not in use, and at least one stabilising member disposed above and adjacent the bottom of the box, said stabilising member being movably attached to the box and adapted for disposal in a stowed position within the compass of the box and alternatively in an operative position in which it projects from within the box through said opening means and outwardly beyond the box transversely of the length thereof.

3. A portable projection screen comprising a long box, opening means in the perimeter of said box, a screen sheet adapted to be extended for use upwardly from the box and to be housed in the box when not in use, and at least one stabilising member disposed above and adjacent the bottom of the box, said stabilising member being pivoted to the box within the latter and adapted for disposal in a stowed position within the compass of the box and alternatively in an operative position in which it projects from within the box through said opening means and outwardly beyond the box transversely of the length thereof.

4. A portable projection screen comprising a box, opening means in the perimeter of said box, a screen sheet adapted to be extended for use upwardly from the box and to be housed in the

box when not in use, and at least one stabilising member disposed above and adjacent the bottom of the box, said stabilising member being longer than the width of the box from front to back and being pivoted between its ends to the bottom of the box and adapted for disposal in a stowed position within the compass of the box and alternatively in an operative position in which it projects from within the box through said opening means and outwardly beyond the box transversely of the length thereof.

5. A portable projection screen comprising a long box, longitudinal slots being provided respectively in the front and rear walls of said box, a screen sheet adapted to be extended for use upwardly from the box and to be housed in the box when not in use, and at least one stabilising member disposed above and adjacent the bottom of the box, said stabilising member being a flat element of a length greater than the width of the box from front to back and being pivoted midway between its ends to the upper side of the bottom of the box on the longitudinal centre line of such bottom, and said stabilising member being adapted to be swung through a right angle from a stowed position within the compass of the box to a position in which it projects transversely from the box through said longitudinal slots.

6. A portable projection screen according to claim 5, wherein the said stabilising member has a dependent foot at each end and the box is recessed to receive these feet when the stabilising member is stowed.

7. A portable projection screen comprising a long box, recesses being provided in the front and rear walls and bottom of said box, a screen sheet adapted to be extended for use upwardly from the box and to be housed in the box when not in use, and at least one stabilising member disposed above and adjacent the bottom of the box, said stabilising member being a flat element of a width equal to and of a length greater than the width of the box from front to back and being pivoted midway between its ends to the upper side of the bottom of the box on the longitudinal centre line of such bottom, and said stabilising member being adapted to be swung through substantially a right angle from a stowed position within the compass of the box to a position in which it projects transversely from the box through longitudinal slots provided respectively in the front and rear walls of the box, and a dependent foot at each end of said stabilising member, such feet being adapted to be received, when the stabilising member is stowed, in said recesses.

8. A portable projection screen comprising a long box, recesses being provided in the bottom of said box, a screen sheet adapted to be extended for use upwardly from the box and to be housed in the box when not in use, and at least one stabilising member disposed above and adjacent the bottom of the box, said stabilising member being a flat parallelogram-shaped element of a width equal to, and of a length greater than, the width of the box from front to back and being pivoted midway between its ends to the upper side of the bottom of the box on the longitudinal centre line of such bottom, and said stabilising member being adapted to be swung through substantially a right angle from a stowed position within the compass of the box to a position in which it projects transversely from the box through longitudinal slots provided

respectively in the front and rear walls of the box, and a dependent foot at each end of said stabilising member, such feet being adapted to be received, when the stabilising member is stowed, in said recesses.

9. A portable projection screen according to claim 8, wherein the said longitudinal slots in the front and rear walls of the box are equal in length to the longitudinal parallel edges of said stabiliser and are relatively offset to the same extent as these edges.

10. A portable projection screen comprising a long box, opening means in the perimeter of said box, a screen sheet adapted to be extended for use upwardly from the box and to be housed in the box when not in use, and at least one stabilising member disposed above and adjacent the bottom of the box, such stabilising member being anchored to the box for guided sliding movement in a direction transversely of the length of the box and being adapted for disposal in a stowed position within the compass of the box and alternatively in an operative position in which it projects from within the box through said opening means and outwardly beyond the box transversely of the length thereof.

25

11. A portable projection screen according to claim 10, having at least a pair of said stabilising members, one adapted to be projected through the front wall and the other through the rear wall of the box.

12. A portable projection screen comprising a long box, opening means in the perimeter of said box, a screen sheet adapted to be extended for use upwardly from the box and to be housed in the box when not in use, and at least one pair of stabilising members, each of these members being pivoted to the bottom of the box within the latter and each being adapted for disposal in a stowed position within the compass of the box and alternatively in an operative position in which it projects from within the box through said opening means and outwardly beyond the box transversely of the length thereof, and the two stabilising members of the pair being adapted, in their operative positions, to project in opposite directions from the box.

13. A portable projection screen according to claim 12, wherein the stabilising members of the pair are pivoted upon a common pivot.

JOHN LESLIE STABLEFORD.
